(57) **CLAIM**

The ornamental design for a sliding door bracket assembly, as shown and described.

DESCRIPTION

FIG. 1 is a front, right-side, top perspective view of the sliding door bracket assembly, showing the new design in an unassembled configuration separated into a top art and a bottom part.

FIG. 2 is a front elevational view of the top part;

FIG. 3 is a rear elevational view of the top part;

FIG. 4 is a left-side elevational view of the top part, the right-side elevational view (not provided) being a mirror image thereof;

FIG. 5 is a top plan view of the top part;

FIG. 6 is a bottom plan view of the top part;

FIG. 7 is a front elevational view of the bottom part;

FIG. 8 is a rear elevational view of the bottom part;

FIG. 9 is a left-side elevational view of the bottom part, the right-side elevational view (not provided) being a mirror image thereof.

FIG. 10 is a top plan view of the bottom part;

FIG. 11 is a bottom plan view of the bottom part; and,

FIG. 12 is a front, right-side, top perspective view of the sliding door bracket assembly in an assembled configuration.

The broken lines depict parts of the sliding door bracket that form no part of the claimed design.
